CRIBBER CHAIN EXCAVATING ELEMENT

Harry W. Protzeller, Milwaukee, Wis., assignor to
 Nordberg Manufacturing Company, Milwaukee,
 Wis., a corporation of Wisconsin

Application September 16, 1946, Serial No. 697,309

5 Claims. (Cl. 37—191)

1

My invention relates to an improvement in digging flights.

One purpose is to provide a digging flight which can be advantageously used with excavating chains.

Another purpose is to provide a digging flight which is particularly adapted for use in cribbing machines which excavate the ballast from between the ties of a railroad track.

Another purpose is to provide a flight which is adaptable for use with two parallel chain components.

Another purpose is to provide a flight which forms part of and connects to parallel chain components.

Other purposes will appear from time to time in the course of the specification and claims.

I illustrate the invention more or less diagrammatically in the accompanying drawings wherein:

Figure 1 is a front elevation of a shovel flight;

Figure 2 is an end elevation of the structure of Figure 1;

Figure 3 is a bottom view of the structure of Figure 1;

Figure 4 is a front elevation of a flight having a plurality of excavating picks;

Figure 5 is a section on the line 5—5 of Figure 4;

Figure 6 is a front elevation of another flight, 30 having a different arrangement of picks;

Figure 7 is a similar view of a flight, having a still different arrangement of picks;

Figure 8 is a side elevation of a typical chain assembly with which my flights can be employed;

Figure 9 is a section on an enlarged scale of the line 9—9 of Figure 8; and

Figure 10 is a diagram illustrating more or less diagrammatically the contour of the cut or excavation made by the excavating elements herein described.

Like parts are indicated by like symbols throughout the specification and drawings.

Referring to the drawings, and first to Figures 8 and 9, I illustrate a boom assembly 1 which, of itself, forms no part of the present invention, but which indicates a typical use of a chain including flights of the type herein described and claimed. 2 is a drive sprocket having teeth 3, separated by pintle engaging gaps 4. 5 is a sprocket shaft. It will be understood that the sprocket or the shaft may be driven from any suitable power source not herein shown. It will be understood that two sprockets may be employed, separated along the axis of the shaft 5.

2

6 indicates any suitable idler roll on its shaft 7. 8 indicates a digging beak which forms part of the boom 1. 9 is an end roller with its shaft 10, about which the chain passes. I do not illustrate the chain in detail, but it will be understood that I may employ a plurality of side link members 30 or 40 connected by pintles 50, with upset locking ends 50a. The arrangement of the two chains is well shown in Figure 9. The chains 10 are shown as passing around the reverse guide flanges 25 having a beveled entry portion 26. 27 is an oppositely beveled entry portion of the boom structure. The beak portion 8 has upper guide flanges 14 and lower guide flanges 17, extending outwardly from side members 15 mounted at opposite sides of the boom component 11. Any suitable securing means may be employed, such as the locking bolts 19, headed as at 20, and provided with nuts 21. It will be observed that the 20 inwardly projecting link members 40c, of the inner chain portion D, engage the underside of the flanges 14. This will be clear from Figure 9. This relationship is maintained from the curved guide portion 25 of Figure 8 to the end of the 25 flanges 14, adjacent the roller 9, as shown in Figure 8. On the return or excavating portion of the chain excursion, the entire width of the chain structure bears against the lower face of the flanges 17, as shown in Figure 9.

Whereas the details of the chain do not of themselves form part of the present invention, it will be understood that the chain side members 30 may be connected by hollow sleeves 35, surrounded by rollers 36. Other side chain members 40 may directly engage the pintles 50, without the use of intervening tubes or cylinders. Thus I employ two parallel chains, each chain having roller components and non-roller components.

40 Connecting the two chains, and forming part of them, I provide a series of excavating members. Some are indicated as picks and some as shovels. The two chain components, which I may indicate as A and B in Figure 9, are connected by the flights generally indicated as E. These various flights are indicated in detail in Figures 1 to 7, inclusive. Each such flight includes a transversely extending body 60, from one face of which projects any suitable digging or excavating element. In the form of Figure 1, I illustrate a single shovel 61, having a sharp forward cutting edge 62, and a somewhat steeper rear face 63. The bottom face of the shovel is upwardly and rearwardly inclined, as at 64. The digging face 65 joins the inclined forward face

66 of the flight body 60. Extending from the opposite face of the flight body 60, I illustrate pairs of lugs 70. The lugs are separated by a space proper to receive one of the roller link units. The lugs are formed generally like the side link members 30 or 40, as will be clear from Figures 2 and 5. Thus the lugs 70 are formed to act as integral parts of the chain structure, and, when flights are inserted in the chain, to take the place of pairs of the side link members 40. Preferably the width of the lugs, transversely of the chain, is twice that of the members 40. The lugs 70 are provided with apertures 71, through which the pintles 50 may pass.

When my chain is employed for excavation, it may be advantageous to provide a plurality of flights having different digging elements. For example, in Figure 4, I employ a plurality of picks 75, 76, 77, the pick 76 being on the center line of the entire chain structure, while the picks 75 and 77 are each aligned with one of the chain components A or B. In Figure 6, I employ two widely spaced picks 78, 79, each of which is generally aligned with one of the chain components. In Figure 7, I also illustrate two picks 80, 81, somewhat out of line with the chain components. In all forms the picks, or the shovel 61, are symmetrically arranged in relation to the center line of the entire chain structure, this center line being indicated at O in Figures 1, 4, 6 and 7. Also, it is preferable that all of the pick members be forwardly inclined, as is shown in Figure 5, and conform generally to the contour above described in connection with the shovel element 61. It is advantageous that the outer edge portions be beveled or downwardly and inwardly inclined, as at 82 in Figure 1, 83 in Figure 4 and 84 in Figure 6. Since the members 80 and 81 of Figure 7 are located substantially inwardly from the sides of the cut or excavation made by the chain, they need not be thus formed.

It is advantageous to arrange the flights uniformly along the chain, as shown in Figure 8, with the various types of excavator tool arranged in any desired order and relationship. This may depend upon the nature of the material being excavated. Soft material might require only shovel members 61. Hard material might require more of the picks, as shown in Figures 4, 6 and 7.

The two chain components A and B are thus spaced apart and maintained in substantially fixed spaced relationship. The symmetrical arrangement of the excavating tools prevents any substantial side stress or twisting of the chain. The sequence of different types of picks and shovels insures that even the hardest soil will be broken up, and will be conveyed out of the excavation in the course of the normal movement of the chain.

It will be realized that whereas I have described and shown a practical and operative device, nevertheless many changes in size, shape, number and disposition of parts may be made without departing from the spirit and content of my invention. I therefore wish my description and drawings to be taken as in a broad sense illustrative or diagrammatic, rather than as limiting me to my specific showing herein.

The use and operation of the invention are as follows:

The present excavating elements should be considered in connection with the particular function which they perform. They are employable with a cribbing machine, the function of which is to remove ballast from between the ties of a track,

from the so-called cribs, or spaces between the ties. The cribbing machine functions without the removal of the rails from the ties and, as shown in Figure 8, includes a chain carrying boom which may be inserted, between the ties, and below the rails. The cribbing machine may be used either to remove ballast permanently, the removed ballast being wasted, and replaced by new ballast, or it may be used to remove ballast to be cleaned and thereafter returned. In either event, the adequate removal of the ballast is but one factor of the successful operation. Especially where the ballast is to be removed and then returned after screening and cleaning, and, when there is no substantial rebuilding of the track and the track supporting mass, there should be a minimum disturbance of that part of the ballast which is not removed. Figure 10 illustrates diagrammatically the contour of the cut which is made by the excavating elements, in relation to the ballast which actually underlies the ties.

The ballast is usually packed very compactly with power tampers, around and under the ties. This packing extends inwardly from the tie ends to approximately one foot from the center of the tie. The center portion is loose. The packing which is secured by this tamping is further consolidated by the traffic over the rails, which tends still further to compact the ballast. Thus a very hard "bed" results directly under the ties. So far as possible, any cribbing out of the ballast should not disturb this bed. The tendency of ballast, under traffic and weather conditions, is to reduce the size of the individual pieces. A powder, mixed with mud and clay, often forms so-called cemented ballast. It is practically impossible to break up this cemented ballast, except with sharp pointed tools forced into it with great force. In order to break up this cemented ballast, I provide the pointed tools shown, for example, in Figures 4 to 7, inclusive. By alternating sharp pointed flights with the broad surfaced flight of Figure 1, I secure a breaking action with which is associated a simultaneous conveying or removing action.

In each crib section or space there is a combination of ballast materials, bounded by the wooden faces of the ties, and often bonded to the tie surface. It is important to remove the mud, dirt and debris that clings to the tie without damaging the tie itself. I obtain this result by employing excavating elements having end cutting surfaces or edges. As will be clear, for example, from Figures 1 and 3, I form a rather blunt and backwardly raked scraping edge at 100. This edge, as will be clear from Figure 1 or Figure 4, is located above the cutting level of the downwardly extending tools or points 75, 76 and 77 of Figure 4. Thus, while the downwardly extending tool portions penetrate below the level of the tie bottoms, as shown at X in Figure 10, the end edges 100 are positioned to operate against the cemented ballast along the lower part of the side faces of the ties. The preferred contour, which is obtained by oscillating the conveyor chain backwardly and forwardly along the track, while the chain is performing its excavating function, includes shallow, horizontal ledges 101, adjacent the ties, a downwardly and inwardly inclined slope 102, and a generally flat bottom 103. These shelves or ledges 101 may be approximately an inch wide, to give an example, and the downward slopes 102 may approximate 45°. The floor or bottom 103 should be several inches below the tie bottoms to provide for drainage.

The shape of the excavating elements should also be considered in relation to the removal of the material. Referring to Figure 8, as the conveyor elements pass about the idler 10, they encounter ballast that must be loosened up and dragged out. All of the excavating members have a forward rake or inclination. This inclination is provided so that the outer point of each digging element encounters the ballast first, so that a digging instead of a slapping action results. Thus the forward edge 62 of the broad member 61, and the corresponding edge of each of the other excavating elements actually enters the ballast with a true digging action. As the excavating elements pass along and under the lower side of the boom, the angle of inclination thus provided serves to maintain a simultaneous lifting and dragging action. This will be clear from an inspection of the lower part of Figure 8. The inclination of the excavating elements necessarily has a lifting action on the ballast particles. As the excavating elements pass to the upwardly and outwardly inclined end portion of the boom, the angle of the inclination is such that an upwardly and outwardly discharging action takes place. The particles are actually upwardly lifted or propelled, in addition to the outward movement, and the material is, in practice, thrown clear and deposited along the right of way or in the inter-track space of a multiple track line. The present elements have been designed to perform satisfactorily all of the above three functions, namely, the initial digging action, the combined lifting and lateral conveying action, and the final upward and outward discharging action.

In connection with a double chain structure for cribbers, I thus provide a highly efficient flight which connects two parallel chain components, and which also serves as a link part of each of the components. I illustrate various conformations and arrangements of digging elements on these flights. I find it advantageous to space the flights closely along the chain components, as shown, for example, in Figure 8. I also find it advantageous to arrange the excavating projections in a balanced or symmetrical arrangement at opposite sides of the central line of the entire chain element. As shown, for example, in Figures 1 to 7, the shovel 61 is centered on the O line. In Figure 4 a tooth or pick 76 is on center, and the side picks 75 and 77 are equally spaced at opposite sides of center. In Figures 6 and 7, where only two picks appear, they are equally spaced at opposite sides of the center line. All forms of the flight have in common that they are interchangeable with link elements and may be inserted in the two chain components.

I claim:

1. As a new article of manufacture, an integral digging flight adapted for use in an excavating chain, said flight including a transversely extending body portion with cutting edges at opposite ends thereof, said body portion having chain receiving lugs extending from one face thereof, said lugs having laterally spaced pintle receiving apertures spaced from said face of said body portion a distance less than the distance between said apertures, said apertures being spaced substantially equidistant from said body portion and the outer edge of said lug, and a plurality of transversely spaced upturned picks extending from the opposite face of said body portion, the base of said picks being spaced from said one face of said body portion a distance less than that between the apertures in said lugs, the outer edges of

said picks being spaced inwardly from the cutting edges on said body portion.

2. As a new article of manufacture, an integral digging flight adapted for use in an excavating chain, said flight including a transversely extending body portion with cutting edges at opposite ends thereof, said body portion having chain receiving lugs extending from one face thereof, said lugs having laterally spaced pintle receiving apertures spaced from said face of said body portion a distance less than the distance between said apertures, said apertures being spaced substantially equidistant from said body portion and the outer edge of said lug, and a plurality of transversely spaced upturned picks extending from the opposite face of said body portion, the base of said picks being spaced from said one face of said body portion a distance less than that between the apertures in said lugs, said lugs and picks being symmetrically arranged at opposite sides of the center of said body portion, the outer edges of said picks being spaced inwardly from the cutting edges on said body portion.

3. As a new article of manufacture, a unitary metal digging flight adapted for use in excavating chains, said flight including a transversely extending body portion, said body portion having apertured chain pin receiving lugs extending from its upper face and a digging element extending downwardly from its lower face, said flight having lateral digging edge portions at the opposite ends of said body portion, said lateral digging edge portions being located at a level below said chain receiving lugs and above said digging elements and substantially aligned with the body portion of the flight, said digging element extending longitudinally of the body of the flight and terminating at either end inwardly of the extremities of said flight and inwardly of said lateral digging edge portions.

4. As a new article of manufacture a unitary metal digging flight adapted for use in a ballast cribbing chain, said flight including a transversely extending body portion, said flight having lateral backwardly raked blunt digging edge portions at the opposite ends of said body portion, said flight having a cutting tool projecting from one face of said body portion, said cutting tool being provided with working edges disposed in angular relation to each other and to said digging edge portions, one of said working edges being arranged below and substantially perpendicular an adjacent one of said digging edges and being shorter than the transverse extent of said flight and spaced inwardly from one end thereof, another of said working edges extending upwardly from an outer end of said first-mentioned working edge towards said adjacent blunt digging edge, chain pin receiving lugs extending from the opposite face of said body portion in substantially perpendicular relation to the plane of said body portion and substantially parallel to the plane of said lateral digging edge portions, and apertures in said lugs, the axes of which are generally parallel with the transverse extension of the body portion, said body portion being generally rectilinear in transverse extension.

5. The structure of claim 4 characterized by and including apertured chain receiving lugs arranged in pairs, said pairs being spaced inwardly from the ends of said body portion, the cutting ends of said body portion being exterior to the outermost lugs of each pair.

HARRY W. PROTZELLER.
